UNITED STATES PATENT OFFICE.

JOHN MUSIAL, OF UNIONTOWN, PENNSYLVANIA.

LIFE-SAVING DEVICE.

Application filed May 6, 1927. Serial No. 189,245.

This invention relates to new and useful improvements in life preservers for use in the water and aims to provide a highly novel, simple and inexpensively constructed air bag, that may be used singly or that may be readily attached to others to provide a light raft, which raft may be if desired, attached to a vessel lifeboat, whereby in the first instance means are provided for supporting 10 one or two persons in the water, and in the second instance providing a large supporting raft, or in the third instance, a means preventing a lifeboat from turning over in rough water is provided.

15 In the drawings wherein like references indicate like parts:—

Figure 1 is a top plan view of a plurality of my life saving devices interconnected to provide a life raft or a means for supporting 20 a life boat.

Fig. 2 is a detail longitudinal section through one of the devices, taken substantially on the line 2—2 of Fig. 1.

Fig. 3 is a detail transverse section taken 25 substantially on the line 3—3 of Fig. 1.

Fig. 4 is an enlarged fragmentary section substantially on the line 4—4 of Fig. 1, for more clearly disclosing the means whereby a hand strap may be attached thereto, and

30 Fig. 5 is a fragmentary section through the ends of a pair of the devices, equipped to enable the same to be joined, there being disclosed in side elevation, a preferred manner of interconnecting a pair of the devices.

35 Now having particular reference to the drawings, my novel device consists of a substantially rectangularly shaped air bag 5 preferably of rubber, arranged within a non-stretchable but flexible covering 6, preferably 40 of a pair of sections, the edges of which are arranged laterally around the entire area of the bag and interconnected by rivets 7.

45 Arranged between the lateral edges of the covering section is a strip of non-stretchable material 8 while arranged longitudinally over the top and bottom sides of the bag covering at the centers thereof are straps 9—9 also of nonelastic material, the ends thereof being attached to the rivets 7—7 50 interconnecting the edges of the covering section, 6—6, and intermediate strip 8.

At the top of the device, and at the center thereof is arranged a threaded pin 10, the lower end of which is equipped with a disk 11, this pin extending through the upper 55 covering section 6, the upper longitudinal strap 9, and a washer 10, the disk 11 being arranged between a washer 12, and the air bag 5 as clearly indicated in Fig. 4.

Threaded upon this pin is a plate nut 13, 60 to prevent the same from becoming loose with respect to the device. The upper end of the pin is formed with an opening 14 within which is loosely arranged a ring 15 and to which is attached the inner end of 65 a strap 16. This strap is formed with a longitudinally extending hand hold 17, for obviously permitting one in the water to easily grasp the device, or in the event a plurality of the devices are interconnected, 70 to enable those sitting or standing thereon to tightly hold on.

The flange provided around the entire area of the device by reason of the outwardly extending edges of the covering sections 6, is 75 provided at predetermined points with metallic grommets 18. Arranged within certain of these grommets are swivel rings of the character indicated in Fig. 5, and designated at 19, and with each of which is 80 associated a conventional spring latch hook 20. These swivelly attached hooks are provided for the purpose of permitting a number of the devices to be interconnected to provide a raft as in Fig. 1, and also to 85 permit the raft to be secured to a rope A, arranged around the gunwale of a life boat B, see Fig. 1.

It will thus be seen that I have provided a highly novel, simple and relatively inexpensive life saving device which is well adapted for all of the purposes heretofore designated, and even though I have herein shown and described the invention, as consisting of certain detail structural elements, 90 it is nevertheless to be understood that some changes may be made therein without affecting the spirit and scope of the appended claim.

Having thus described my invention, what 100 I claim as new is:—

In a life saving device of the character

described, an air bag, a rectangular casing for the bag, consisting of a pair of sections, the edges of which are mounted laterally around the bag to provide a flange, a rectangular reinforcing frame between the edges of the sections and connecting means between the edges and said reinforcing means, and means located at spaced points

around said flanges to permit the interconnection of a plurality of the devices to provide a raft, said means consisting of grommets associated with the flange and swivel hooks arranged within the grommets.

In testimony whereof I affix my signature,

JOHN MUSIAL.
